J. B. Okey,
Making Laths.

No 16,493.

Patented Jan. 27, 1857.

Fig. 2.

Fig. 1.

UNITED STATES PATENT OFFICE.

JOSEPH B. OKEY, OF INDIANAPOLIS, INDIANA.

LATH-MACHINE.

Specification of Letters Patent No. 16,493, dated January 27, 1857.

To all whom it may concern:

Be it known that I, JOSEPH B. OKEY, of the city of Indianapolis, in the county of Marion, State of Indiana, have invented a new and useful Machine for Cutting Laths; and I do hereby declare that the following is a full, clear, and exact description thereof, reference being had to the accompanying drawing, through letters of reference marked thereon, forming part of this specification, in which—

Figure (1) represents a top view of my machine, and Fig. (2) a transverse section through the center.

15 My invention relates more particularly to that class of machines in which the laths are severed from the blanks by a lateral or transverse cut crossing the grain of the wood; and it consists in arranging a series of cells, 20 (for the reception and support of the blanks while being cut up into laths) and a series of gage stops to regulate their thickness, in arcs of concentric circles, upon the axis of which is mounted, and vibrates the knife, or 25 knives by which the laths are cut from the blank.

30 My invention further consists in arranging and securing, upon a cutter head having a vibrating motion, a double or two edged knife, whereby laths may be cut, as well in its backward as in its forward stroke, thus economizing time and equalizing the labor of cutting.

35 To enable others to make and use my invention, I will now proceed particularly to describe its construction and operation.

The frame (A) of my machine is constructed of iron or wood, the upper part being formed in the arc of a circle described 40 from a journal (B) in the lower cross tie of the ends of the frame; extending from end to end, and connected with the upper ribs (a) of the end frames, are a series of strips (C) which are returned upward at each end, 45 and form cells (D) for the insertion of the blanks, between the sides of which they are supported as they are being cut up into laths, these cells are made of sufficient size to allow the blanks to pass through freely by their 50 own weight, beneath, and at a suitable distance apart from each cell, and at each end

thereof is placed a projection or gage stop (E) for the blanks to rest upon, which forms the gage for the thickness of the lath, these stops being arranged upon adjustable 55 heads so that they may be raised or lowered, to increase or diminish the thickness of the laths as required.

On the rock shaft (B) which is supported in bearings at each end of the frame are 60 mounted two bow, or stirrup levers (G) to the upper ends of which the knives (H) are attached. Motion is communicated to these by means of a belt, from "steam engine" or motive power, passing over the pulley (I,) 65 which causes the shaft (J) to rotate when the cams (K,) which are fast thereon rotate within the stirrup (G), and cause them with the knives which are rigidly attached to their upper ends to oscillate upon the axis B, and thus cut the laths, from the underside 70 of the blanks in the series of cells alternately by the backward and forward motion of the knives. The laths on being severed fall beneath as the knife recedes from under the 75 blanks, the latter dropping down upon the gage at the same time in readiness to be again cut upon the return of the knives. This arrangement might be slightly varied 80 by having but one series of cells, arranged centrally over the rock shaft B, instead of on either side, and a two edged knife oscillating so as to cut from the same blanks both in its backward and forward motion.

Having thus described my invention, what. 85 I claim as new, and desire to secure by Letters Patent is.—

The arrangement of one or more series of cells (D) and their gage stops (E) in the arcs of concentric circles for the reception 90 of the blanks in combination with an oscillating knife or knives (H) mounted and operating in the manner substantially as and for the purposes specified.

In testimony whereof I have hereunto 95 signed my name this third day of October A. D. 1856.

JOSEPH B. OKEY.
